UNITED STATES PATENT OFFICE.

CASPER FAUST, OF OSHKOSH, WISCONSIN.

BOLSTER-STAKE HOLDER.

1,217,584.

Specification of Letters Patent. Patented Feb. 27, 1917.

Application filed December 18, 1916. Serial No. 137,565.

To all whom it may concern:

Be it known that I, CASPER FAUST, a citizen of the United States, and resident of Oshkosh, in the county of Winnebago and 5 State of Wisconsin, have invented certain new and useful Improvements in Bolster-Stake Holders; and I do hereby declare that the following is a full, clear, and exact description thereof.

10 The present invention relates to new and useful improvements in bolster stake holders, more particularly of that type embodied in Patent No. 1,082,074, granted to me December 23, 1913, and comprising a 15 socket member including portions hinged to swing open to release the bolster stake and having latch means associated therewith for holding said portions in closed position.

20 It is in general the object of the invention to simplify and otherwise improve the structure and to improve the efficiency and readiness of operation of devices of this nature.

25 More specifically, an object of the invention resides in the provision of an arrangement wherein the latch means of the socket sections is relieved from strain when the sections are closed and holding a bolster stake.

30 A further object resides in the provision of a bolster stake holder adapted more particularly for use in metallic car structures wherein a snug metallic fit is afforded the bolster stake to obviate the necessity of providing wear plates thereof.

35 A still further object is to provide an arrangement whereby in closing the latch means of the stake holder, a cam action is exerted on the socket members to urge them 40 to a proper position to snugly engage a bolster stake disposed therein.

With the above and other objects in view, the invention resides more particularly in the novel combination, arrangement, and 45 formation of parts, more particularly hereinafter described and particularly pointed out in the appended claims.

In the drawings:

Figure 1 is a side view of a portion of a 50 metallic car frame showing the improved bolster stake holder associated therewith.

Fig. 2 is a horizontal view of the line 2—2 of Fig. 1.

Fig. 3 is a vertical sectional view taken 55 transversely through the car frame show-

ing the method of attachment of one of the socket sections thereto.

Referring now more particularly to the accompanying drawings, 5 designates a channeled side sill of a car of metallic construction, and 6 designates a cross sill thereof.

The present stake holder comprises, as in the structure of my said previous patent, a pair of arcuate socket sections 7 and 8 respectively and to hingedly secure these sections to the sill 5 in such manner that the sill forms the inner wall of the socket, the inner end of each section is reduced and carries the vertical pintles 9 engageable in a pair of vertically aligned upper and lower bearing blocks 10 and 11 respectively.

For locking the socket sections together the section 7 is cut away at its outer portions to provide a flat face 12 and the free edge of the socket section 8 is provided with an intermediate opening, the inner end portions of which are extended to form recesses 13 and pivoted to the socket section 7 on the surface 12 are a pair of locking arms 14 which are adapted to extend into the recess of the socket section 8 and which have lateral projections 15 at their free ends engageable in said recesses 13.

For holding the arms in this locking position a pair of pivotally connected links 16 are provided with their outer ends pivoted to the arms and connected to the links preferably by means of the common pivot bolt thereof, is a latch bar 17 extending toward the socket section 7 and having its free end laterally directed and apertured to engage over a lug 18 on the side of said socket section which is adapted to receive a locking pin 19 whereby undesired opening movement of the socket is prevented. To release the locking arms, upon removal of the pin, it is merely necessary to pull the latch bar 17, and a continued pulling movement of the bar will swing the socket section 7 open 100 to insure displacement of the bolster stake from the socket. For procuring this pulling movement from the end of the car, a chain 20 is secured to the latch bar.

The foregoing locking arrangement for the socket sections is exceedingly simple in structure and positive in operation, and it is noted that the major portion of the strain of holding the socket sections closed is exerted on the locking arms 14, thus the latching 110

means including the latch bar 17, is relieved from such strain. Inasmuch as the outer side walls of the recesses 13 and the adjacent faces of the locking arm extensions 14 are 5 beveled, it is seen that movement of said extensions into the sockets 13 will procure a camming action of the socket member 8, to draw both socket members together to thus insure a snug fit of the bolster stake disposed therein.

10 Inasmuch as the socket sections 7 and 8 and the car sill 5 are of metal, and comprise the entire socket the necessity of providing wear plates on the lower end of the bolster 15 stake is obviated, particularly in view of the snug fit afforded the stake by the cam action of the locking arms.

What is claimed is:

1. A bolster stake holder comprising a 20 socket member including a hinged portion, a locking arm pivoted to the socket member and adapted for detachable interlocking engagement with the hinged portion, a link pivoted to the locking arm, a latch bar connected to the link and means for locking 25 said latch bar against movement.

2. A bolster stake holder comprising a 30 socket member comprising a pair of hinged portions, a locking arm pivoted to one of the hinged portions and adapted for detachable interlocking engagement with the other

hinge portion and means operable upon movement in the direction of hinge movement of the hinge portions for moving said locking arm out of interlocking engagement. 35

3. A bolster stake holder comprising a socket member including a hinged portion provided with recesses a pair of arms hinged to the socket member, lateral projections on said arms adapted for interlocking engagement in the recesses, pivotally connected links pivoted to the locking arms, a latch bar connected with the links and means for locking said latch bar against movement. 40

4. A bolster stake holder comprising a 45 socket member including a hinged portion, a locking arm pivoted to the socket member and adapted for detachable interlocking engagement with the hinged portion, a link pivoted to the locking arm, a latch bar connected with the link and means for locking 50 said latch bar against movement, and said locking arm and hinged socket portions including inclined portions adapted to procure a cam action upon movement of the locking arm to operative position for drawing the hinged socket portion to closed position. 55

In testimony that I claim the foregoing I have hereunto set my hand at Milwaukee, in the county of Milwaukee and State of Wisconsin. 60

CASPER FAUST.
